UNITED STATES PATENT OFFICE

OSCAR WILHELM, OF HUNTINGTON, WEST VIRGINIA

GAS-BURNER ATTACHMENT

Application filed February 28, 1929. Serial No. 343,373.

This invention relates to an auxiliary top for a gas burner, and is more particularly concerned with a new and useful improvement whereby the efficiency of combustion and radiation of heat is greatly enhanced.

An object of my invention is to produce an auxiliary top for a burner whereby an enormous increase in the efficiency of combustion and heat radiation is produced.

10 Another object is to produce an auxiliary top for a burner having an elevated plateau provided with a plurality of openings therein, circumferentially arranged, a gently sloping downturned peripherally arranged flange, 15 and a substantially centrally located depressed portion, whereby the ignited fuel from the burner is directed upwardly and outwardly by said depressed portion to insure complete combustion and efficient radiation of the heat.

Still another object is to produce an auxiliary top for a burner having an elevated plateau provided with a substantially centrally located depressed portion, a plurality of orifices circumferentially arranged about said depressed portion, a peripherally located, gently sloping downturned flange, and a plurality of apertures arranged at the juncture of the flange with the elevated plateau, where- 20 by the ignited fuel from the burner is directed upwardly and outwardly by said depressed portion where it is completely mixed with cross currents of air provided by the last mentioned apertures, and is passed 25 upwardly, in its completely ignited condition, through the first mentioned apertures.

Other objects will appear hereinafter.

In the drawings,

Fig. 1 is a side elevation of a gas stove 40 having a burner employing an auxiliary top according to my construction;

Fig. 2 is a perspective view illustrating one form of auxiliary top according to my construction;

45 Fig. 3 is a vertical section taken through the center of the top illustrated in Fig. 2, while

Fig. 4 is a vertical section through a modified form of top.

50 At 1 is shown a small representation of

the usual form of stove, having a top 2, a source of fuel supply 3, the usual type of burner cock 4, a mixing chamber 5, and a supply pipe 6 to the burner 7. The supply pipe 6 and burner 7 may be supported from the stove top 2 by hangers or other suitable means 17. This construction is of the ordinary type, and may be varied at will without departing from the novel features of my invention.

Resting on the burner 7 of Fig. 1, an auxiliary top according to my invention is broadly indicated by the reference numeral 8. The top 8 preferably has an elevated, 65 substantial level portion 9, forming a plateau, which terminates at its inner periphery in a substantially centrally located depressed portion 10 having inwardly sloping walls 11. The bottom of the wall is defined by a central opening 12. Arranged about the inner periphery of the elevated portion 9 are a plurality of circumferentially located openings 13. The outer extremity of the level portion 9 is defined by a gently sloping downwardly- 70 turned annular flange 14 by means of which the top is supported from the burner 7, and which also provides a seal therebetween. Formed in the top 9 and extending outwardly 75 into the flange 14, are a plurality of openings 15, which serve the function of providing cross currents of air to insure complete ignition of the partially ignited gases deflected from the walls 11.

The burner of Fig. 4 is substantially the same as that of Fig. 3 except that the bottom of the depressed portion defined by the walls 11 is provided with a closure member 16. When a top according to my invention is used on ranges employing gas, oil, or other suitable fuels, with star, round, square, or other shaped burners, it confines the ignited fuel therein, permitting its thorough ignition, and then passes it upwardly either through the openings 13 thereof or as radiant heat, in such manner that it uniformly distributes the heat thereof. This is accomplished as a result of the flame from the burner impinging on the interior wall 11 and being deflected toward the sides of the top, whereby the fuel is thoroughly mixed 105

with air from the openings 15 and ignited, and the resultant flame is passed upwardly through the annular openings 13, a considerable quantity of the heat being also radiated from the top itself.

5 It is immaterial as to whether the device of Fig. 3 or Fig. 4 is employed, inasmuch as the heat is thrown, by means of the sloping walls 11, in a circle around the center, and
10 is not brought to a point at the center of said circle. Special emphasis is laid on the feature of the inner depressed portion having sloping walls, inasmuch as it is these walls which properly direct the ignited fuel into
15 the combustion chamber defined by the elevated portion 9, and the annular flange 14.

It is of course understood that the invention is susceptible to numerous modifications and adaptations; and it is intended that it be
20 limited only by the scope of the appended claim.

I claim:

A gas burner comprising a burner proper, and an auxiliary top raised and supported
25 from said burner by means of an annular flange extending about said top, a plurality of openings arranged circumferentially around the juncture of said flange with said top for providing cross currents of air, said top having a substantially centrally located depressed portion spaced above the lower edge of said flange and having upwardly sloping walls, said top having a plurality of openings arranged circumferentially about the margins
30 of said depressed portion for permitting the passage of the ignited gases, said walls deflecting the ignited fuel from said burner outwardly through said last mentioned openings in a substantially continuous sheet.

40 OSCAR WILHELM.
